OPEN FRONT REFRIGERATED CABINET

Paul H. Brinkoeter, San Antonio, Tex., assignor
to Ed Friedrich, Inc., San Antonio, Tex., a corporation of Texas

Application August 8, 1951, Serial No. 240,833

2 Claims. (Cl. 62—89.5)

1

This invention relates to an improvement in open front refrigerated cabinets, and particularly of the type employed for the display and sale of vegetables.

The invention consists in locating refrigerating coils along the back wall of the cabinet for the delivery of refrigerated air to the food compartment, and in having a second cooling coil at the front of the cabinet arranged beneath the food shelves so that cold air will contact the shelves throughout their length and width and maintain the shelves in a cold condition to transmit cold to the vegetables by conduction.

The invention consists of certain novel features of construction and combinations of parts which will be hereinafter set forth and pointed out in the claims.

In the accompanying drawings:

Figure 1 is a transverse vertical sectional view of the invention; and

Figure 2 is a top plan view partly in section.

The cabinet comprises front, back and end walls, 10, 11 and 12, respectively. A horizontal partition 13 extends lengthwise of the cabinet, and is provided at its front edge and along the inner face of the front wall 10, with a longitudinal trough 14. Brackets 15 and 16 are provided for supporting the partition 13 on the front and back walls 10 and 11, respectively. The partition 13 divides the cabinet into an upper open food compartment 18 and a storage compartment 20. A small bank of finned cooling coils 22 is received in the trough 14 and extend the full length of the cabinet. A division plate 23 is supported adjacent the coils 22, and is spaced from the front wall 10 to provide an outlet air duct or passage 24 for directing the air beneath the coils from the food compartment 18. A perforated cover 25 is mounted over the duct 24 and at the forward edge of the food compartment 18. A thermo-pane glass panel 26 is mounted on the front wall 10 in front of the food compartment 18.

A pressure air duct 28 is arranged along the inner face of the back wall 11 and is supported by the brackets 16. The front panel 29 of the air duct 28 forms the rear wall of the food compartment 18, and provides a support for the rear edge of the partition 13. The back wall 11 of the cabinet is provided with a curved surface or concaved baffle 30 located over the open top of the air duct 28 for directing the cold air over the food compartment 18. Openings 31 are provided in the panel 29 near the top thereof through which cold air will be projected into the food compartment 18.

2

A plurality of imperforate display shelf units are disposed above the partition 13 and between the front wall 10 and panel 29 of the air duct 28 to provide a shelf 33 lengthwise of the cabinet. Each shelf unit is provided with a down turned edge or flange 34, 35 at the ends thereof. The flange 34 is supported by a ledge 36 projecting from the front wall 10 and the other flange 35 is supported on the panel 29 and over the partition 13, as shown in Figure 1. The shelf units are in this manner supported above the cooling coils 22 and partition 13 and provide an air duct 37 therebetween. As indicated in dotted lines the shelf 33 may be adjusted or elevated by having one edge or end of the flanges 35 resting on one or the other of the two ribs 38 formed on the outer face of the panel 29.

Mounted within the air duct 28 are finned refrigerated coils 40, which in this instance are larger than the coils 22 and afford a greater cooling area. The coils 40 are located between the panel 29 of the air duct 28 and the back wall of the duct and back wall 11 of the cabinet. A fan or blower housing 42 is mounted beneath the partition 13 and is provided with a fan 43. The base 44 of the housing is supported by the brackets 15 and 16. A flue or tube 45 connects the housing 42 with the lower portion of the pressure air duct 28 beneath the coils 40.

The partition 13 is provided adjacent its rear edge with rows of perforations or openings 46 which form communication between the horizontal or suction duct 37 and the storage compartment 20. The fan 43 delivers air under pressure into the air duct 28 where it is cooled by the refrigerated coils 40, and the cold air is delivered to the food compartment 18 through the openings 31 in the front panel 29, and over the top of the air duct 29 by the curved baffle 30. The warm air from the food compartment 18 is drawn by the fan 43 through the perforated cover 25 into the duct 24 and trough 14, where the air is directed to the refrigerated coils 22, and then delivered to the suction duct 37. This cold air will cool the shelf 33 and its units, and by conduction the food or vegetables on the shelf will be chilled or frozen. The cold air of the suction duct 37 is delivered to the storage compartment 20 through the openings 46 at the rear end of the partition 13, for the purpose of preserving the vegetables in the compartment 20. The air is withdrawn from the compartment 20 by the fan 43 into the fan housing 42 through an opening 47 in the base 44, and is then delivered to the air duct 28. In this manner the vegetables 55 are subjected to a constant flow or circulation of

refrigerated air and also by conduction through the units of the shelf 33.

I claim:

1. An open front refrigerator, comprising a front wall, a back wall and end walls, an air pressure duct disposed along said back wall and provided with a front panel, a partition extending from said panel to said front wall to provide a food compartment and a storage compartment on opposite sides thereof, a trough formed in said partition along said front wall longitudinally thereof, refrigerating coils in said trough, an outlet duct disposed between said front wall and said refrigerating coils providing an air outlet passage from said food compartment to said refrigerating coils, a removable shelf mounted above said partition and extending over said refrigerating coils and supported by said front wall and said front panel of said air pressure duct, providing a suction chamber between said shelf and said partition, said suction chamber having communication with said storage compartment adjacent said front panel of said air pressure duct, refrigerating coils in said air pressure duct, said air pressure duct having communication with said food compartment, a fan housing mounted beneath said partition and connected to said air pressure duct, said housing having an opening therein to provide communication with said storage compartment, and a fan in said fan housing for circulating air from said storage compartment to said air pressure duct through said fan housing and over said refrigerating coils in said air pressure duct to said food compartment and through said outlet duct and refrigerating coils associated therewith to said suction chamber and into said storage compartment.

2. An open front refrigerator, comprising a front wall, a back wall and end walls, an air pressure duct supported by said back wall and having a front panel, a partition disposed hori-

zontally between said panel and said front wall and supported thereby, said partition having a food compartment and a storage compartment on opposite sides thereof, a trough formed in said partition along the front thereof and adjacent said front wall, refrigerating coils in said trough, an outlet duct located between said front wall and said refrigerating coils for conducting air from said food compartment to said trough and refrigerating coils, a removable shelf disposed above said partition and said refrigerating coils and supported by said front wall and said front panel to provide a suction chamber between said shelf and said partition, said partition having openings therein adjacent said air pressure duct front panel to provide communication between said suction chamber and said storage compartment, said air pressure duct having communication with said food compartment, refrigerating coils mounted in said air pressure duct, a fan housing located beneath said partition having a flue connected to said air pressure duct beneath said refrigerating coils thereof, a base for said fan housing supported by said front and back walls of the refrigerator having an opening therein to provide communication between said storage compartment and said fan housing, and a fan in said fan housing for circulating air from said storage compartment through said air pressure duct and refrigerating coils to said food compartment and through said outlet duct and refrigerating coils to said suction chamber and into said storage compartment.

PAUL H. BRINKOETER.
